IRONING BOARD COVER

Robert G. Cale and Frederick W. Fisher,
Detroit, Mich.

Application November 16, 1934, Serial No. 753,324

5 Claims. (Cl. 38—140)

Our invention relates to an improved ironing board and cover therefor.

An object is to provide a combined ironing board and cover which is of simple and inexpensive construction and which is so arranged and fashioned that the ironing board cover may be quickly placed in position on the board or removed from the board and which comprises a minimum number of simple parts.

Another object is to provide a combined ironing board and cover so formed that while the cover may quickly placed upon the board or removed therefrom it is, when in position, held at all times stretched taut across the upper surface of the board.

A further object is to provide an ironing board and cover of the character above described wherein in the entire covered surface of the board is free from any projecting parts or elements which would interfere or obstruct the free placing and moving of clothes to be ironed upon the board. The under surface of the board, when the cover is stretched taut, is smooth and free from any interfering parts and the cover is at all times held stretched to that degree of tension which is desired and is held securely against accidental displacement or release of the tension imposed thereon.

The above objects and others together with other meritorious features and advantageous characteristics of our invention more fully appear from the following specification, appended claims, and accompanying drawing, wherein:

Figure 1 is a perspective of an ironing board and cover combined embodying our invention and showing the cover stretched in place over the board.

Fig. 2 is a side elevation of a fragment at the base of the board showing our improved combination and illustrating the position of release or relaxing of the cover with respect to the board, and

Fig. 3 is a perspective of a fragment of the cover showing its construction and the manner in which it is adapted to be folded over the board and secured thereto.

In illustrating our invention it is shown as embodied in combination with an ironing board which includes a rigid board element of conventional shape indicated generally as 10. This board is of course provided with suitable supporting means to maintain its required height which means, however, forms no part of our invention and is not here illustrated. In Fig. 1 of the drawing the bottom side of the board is shown upper-

most in order to illustrate more clearly the arrangement of the cover therewith.

The combination includes, in addition to the board, the cover element which is indicated generally as 12 and which comprises a piece of suitable flexible covering material such as fabric of the character required for the purpose. The cover is so shaped as to be received over the board in the manner shown in Figs. 1 and 2 and is of a size to permit of it being folded over the edge of the board on to the underside thereof as shown particularly in Fig. 1. The cover is folded over along both sides of the board and across the tip as shown in such figure of the drawing.

That margin of the cover which is folded over the edge of the board is fastened by stitching 14 or the like to retain a tightening band or element 16 as shown. This tightening band extends continuously and slidably around the margin as illustrated in Fig. 1 and has ends adapted to be secured about the lever 22 as shown in Figs. 1 and 2, to be tightened thereby. This band is formed of cord, wire or other suitable material. Through varying the fastening of the band to the lever the tension established upon the band by the lever 25 may be varied.

The tensioning device is shown in Figs. 1 and 2 and comprises a bracket or base portion 18 which is secured by screws or the like to the underside of the ironing board near the base and approximately midway between the longitudinal edges of the board. A lever 22 is pivoted at 24 to this standard 18 to be thrown forwardly as shown in Fig. 2 to be engaged with the tightening band 16 as there shown when the band is released in its tension. The lever may then be moved toward the base of the board to the position illustrated in solid line in Fig. 1 and in dotted line in Fig. 2 at which position it automatically locks so that the tightening band 16 is held under tension and stretches the cover taut across the outer face of the board. The cover is stretched taut not only lengthwise of the board but as the tightening band is drawn inwardly toward the center of the board from both sides the cover is also stretched taut crosswise of the board.

It will be apparent that the cover may be rapidly removed or placed on the board as desired and that by varying the length of the tightening band or the positioning of the tensioning device the tension which is imposed upon the band to stretch the cover may be readily varied.

The entire under surface of the board is en-

tirely free from any obstructing parts or elements which might catch or obstruct in any way the free disposition or moving of clothes supported upon the board to be ironed and the upper surface is covered with the fabric stretched taut in both directions across the surface of the board.

What we claim:

1. An ironing board combination comprising a board element, a cover element adapted to overlie the top of the board and be folded underneath the board at its tip and along both sides, a tightening band extending slidably around the folded under portion of the cover, and a tensioning device secured to the underside of the board having an open position and a closed position and engaged with the tightening band to tension the same upon movement from its open to its closed position, drawing the cover taut across the upper face of the board in two directions.
2. An ironing board combination comprising a board element, a flexible cover element overlying the top of the board and folded thereunder along both sides of the board and across the tip thereof, a tightening band extending slidably around the folded under portion of the cover, a tensioning device secured to the underside of the board, said band having ends adapted to be engaged with the tensioning device, said tensioning device having two positions at one of which the band is released and at the other of which the band is drawn taut drawing the cover across the top of the board.
3. An ironing board combination comprising a rigid board element having a base end and a tip end, a flexible cover element overlying the top surface of the board and folded underneath the board along both sides and across the tip thereof, a tightening band extending slidably around the folded under portion of the cover, a

tensioning device secured to the underside of the board near its base end and substantially midway between the opposite sides of the board and having a part adapted to be swung toward the tip end of the board and engaged with the released tightening band and adapted to be swung toward the base of the board and locked in such position tensioning the band and drawing the cover taut across the upper face of the board.

4. An ironing board combination comprising a rigid board having a base end and a tip end, a fabric cover adapted to extend over the upper surface of the board and to be folded over the edge and on to the back of the board along both sides and over the tip of the board, a tightening band extending slidably continuously around the cover and engaging therewith and having an end portion extending beyond the cover toward the base end of the board, a tensioning device secured to the underside of the board near the base end spaced from the cover and adapted to be engaged with the adjacent ends of the tightening band to tension the band and draw the cover taut lengthwise of the board and crosswise across the upper surface of the board.

5. An ironing board combination comprising a rigid board having a base and a tip, a flexible cover adapted to extend over the upper surface of the board to be folded over the edge and on to the back of the board along both sides and across the tip of the board, a tightening band extending slidably around the folded over margin of the cover, and means arranged near the base end of the board to which the ends of the band are adapted to be secured and drawn taut to stretch the cover across the face of the board.
